UNITED STATES PATENT OFFICE.

JOHN L. DAWES, OF PITTSBURGH, PENNSYLVANIA; ELIZABETH McCOMBS DAWES
EXECUTRIX OF SAID JOHN L. DAWES, DECEASED.

DESIGN FOR A SIGN.

Application filed June 13, 1922. Serial No. 2,659. Term of patent 3½ years.

To all whom it may concern:

Be it known that I, JOHN L. DAWES, a citizen of the United States, and resident of Pittsburgh, Allegheny County, State of Pennsylvania, have invented a new, original, and ornamental Design for Signs, of which the following is a specification, reference being had to the accompanying drawing, forming part thereof, in which—

I claim:

The ornamental design for a sign, substantially as shown.

In testimony whereof I have hereunto set my hand.

JOHN L. DAWES.
